(57) **CLAIM**

I claim the ornamental design for a task lamp, as shown and described.

DESCRIPTION

FIG. 1 is a front perspective view of the task lamp showing my new design;

FIG. 2 is a front view thereof;

FIG. 3 is a back view thereof;

FIG. 4 is a top view thereof;

FIG. 5 is a bottom view thereof;

FIG. 6 is a left view thereof;

FIG. 7 is a right view thereof;

FIG. 8 is a back perspective view thereof; and,

FIG. 9 is a bottom perspective view thereof.

The broken lines serve to show where a switch could go and form no part of the claimed design.
